UNITED STATES PATENT OFFICE

2,419,996

ROOF GUTTER

Alfred Harold Honikman, Rondebosch, Cape Town, Cape of Good Hope, Union of South Africa

Application April 3, 1946, Serial No. 659,247
In the Union of South Africa April 23, 1945

10 Claims. (Cl. 108—28)

1

This invention relates to roof gutters.

By reason of the prominent position that gutters, gutter accessories and the adjoining discharge pipes frequently occupy in relation to a building, and of the important bearing they have on the appearance of a building they are often concealed or made less conspicuous or obtrusive by means of masonry, timber, metal or other form of casing. Such means require considerable expenditure of labour and materials which necessitate subsequent and expensive maintenance, and render access to the gutter or adjoining pipes difficult or impossible.

The principal object of the present invention is to provide a roof gutter which will be unobtrusive and will obviate the need or desire for concealment by means of additional materials, thereby avoiding extra initial expense and subsequent maintenance.

It is also part of this object of the invention to provide a roof gutter which will obviate the use of the customary brackets for fixing the gutter to the eaves, wall or the like of the building and which will permit the gutter to be laid either horizontally, or to fall, i. e., at an incline.

According to the invention, I provide a roof gutter which comprises gutter-sections adapted to be flush-jointed together with externally concealed laps at all joints to provide an unbroken plane to the outer faces and the soffit or under surface of the gutter, and which also comprises a base flange or projecting member on the gutter-sections which projects downwards and which is adapted to be held or engaged by a base plate, fillet or like member, to be fixed to the eaves, wall or the like of the building.

In order to protect the structural timbers or steelwork of a roof against the effects of rain-water and detrimental atmospheric conditions, a flashing strip at the top inner edge of a gutter is often desirable, but this strip, though well-known, is usually omitted in existing practice on account of cost. It is a further object of the present invention to provide a means which will serve the dual purpose of protecting the structural portions of the roof as aforesaid, while also constituting part of the means for securing the gutter in position.

Another object of the invention is to provide a means of strengthening the gutter against damage due to the weight of ladders resting thereon and workmen employed for painting or maintenance work on the roof.

A further object is to provide a means of

2

preventing blockage of the gutter by leaves and the like or the nesting of birds.

A still further object is to render the gutters adaptable to roofs of different lengths and perimeters in a convenient and inexpensive manner, while simplifying and making more economical the production of the sections of gutter by manufacturing the same in one standardised length, or, at the most, a few standardised lengths.

10 The invention therefore comprises means, additional to the means already indicated for achieving the principal object of the invention, whereby the further objects mentioned above may be attained, such further means being described hereunder and defined in the appended claims.

Flush-jointed gutters embodying the invention will now be described, by way of example, with reference to the accompanying drawings, in which—

20 Fig. 1 is an isometric view of a section of gutter (with parts intermediate the ends broken away) according to the invention.

Fig. 2 is a perspective view of the gutter looking from above, illustrating a joint of the gutter and 25 the cross-section in perspective of the gutter.

Fig. 3 is a longitudinal sectional view of the base of the gutter at the joint.

Fig. 4 a sectional plan view of the joint, taken on a plane passing through the sides of the gutter 30 above the base.

Fig. 5 is a cross-sectional view of the gutter complete inclusive of its parts for fixing it in position.

Fig. 6 is a cross-sectional view of the gutter, 35 showing a modification of the parts for fixing it in position.

Fig. 7 is a diagrammatic view of the gutter and affixing parts, illustrating their relationship in cases where the gutter is laid to fall.

40 Figs. 8 and 9 are cross-sectional views of the said affixing parts and adjacent parts of the gutter when laid to fall, illustrating the relative position of the parts at the lowest and highest points of the gutter respectively.

45 Fig. 10 is an isometric view of a gutter-section illustrating certain of the details shown on a smaller scale in Fig. 5.

Fig. 11 is an external perspective view of the gutter, with parts in isometric section, indicating 50 the appearance of the gutter with respect to the eaves, when viewed from below.

Fig. 12 is a perspective view of a modified form of flush-joint for the gutter, the one end of the joint having a socket of greater length than the

spigot on the other end; parts of the gutter are broken away for clearer illustration.

Fig. 13 is a perspective view of the joint shown in Fig. 12, with the surplus or increased length of the socket end cut away, and the spigot fitting exactly therein, parts being again broken away for clearness.

Fig. 14 is a perspective view of the joint shown in Fig. 12 with a small part of the socket end cut away and the remaining space between the spigot and root of the socket filled-in with a pre-formed filling-piece, parts being broken away for clearness.

Fig. 15 is a perspective view (partly broken away for clearness) of the joint shown in Fig. 12, with a larger part of the socket end cut away, and the remaining space filled-in with material cast in situ.

Referring to Figs. 1 to 11 of the drawings:

As will be seen from Fig. 1, each gutter-section has a back A, front B and base C. At one end of the gutter-section there is formed a spigot having a back D, front E and base F. At the opposite end, a socket G is formed in the floor of the base C.

As shown in Figs. 2, 3, and 4, the spigot D, E, F is adapted to fit neatly into the socket G and adjacent parts of the back A and front B of the adjoining section of the gutter. The overlapping parts are concealed and the joint is flush externally. The floor of the base C of the gutter is also flush throughout.

As will be clear from Fig. 5, a downwardly projecting flange J is formed along the bottom edge of the base C of the gutter-section adjacent to the back A. In fixing the gutter to the eaves of a building, this flange J is held or engaged by a base plate or strip M (Fig. 5), which is adapted to be fixed by nails, screws or the like (not shown, but indicated diagrammatically by two dotted lines in Fig. 5) driven through the rearwardly extending portion of the base plate M from below. At the top the gutter is adapted to be held by a clamp or clamping strip L. The lower part of the clamp L engages over the upper edge of the back A of the gutter, and the nails, screws or the like for attachment of the gutter to the eaves are driven through the upper part of the clamp L from the front as indicated by dotted line in Fig. 5.

The fixture of the gutter by means of the base plate M and clamp L, co-acting with the flange J and back A, eliminates the need for the ordinary brackets, and, besides being more effective and pleasing in appearance, provides "flashing" or protection, by virtue of the clamping strip L, to the roofing material or structural parts adjacent to which the gutter is affixed.

In Fig. 6, an alternative form of base plate or fillet N is illustrated, which may be used when it is required to fix the plate to the eaves from the front instead of from below, i. e., by means of nails, screws or the like driven through the base fillet N in the direction of the dotted line shown in Fig. 6.

In the arrangement shown in Fig. 5, and also shown to a larger scale in perspective in Fig. 10, the outflow of water from the gutter is provided for through a back outlet P. In the alternative, as shown in Fig. 6, a bottom outlet Q may be provided.

As will be seen from Figs. 1 and 2, pairs of oppositely disposed grooves H are formed at intervals in the inner faces of the back A and front B of the gutter. These grooves H, as illustrated in

Figs. 5 and 10, are adapted to receive cross struts or stiffeners K. On top of these struts, a covering grid or perforated slab O is laid. The struts K reinforce the gutter against damage due to external compressive stresses, e. g., caused by ladders resting against the gutter or otherwise. The covering grid or perforated slab O excludes leaves, and prevents nesting of birds and other customary causes of blockage of the gutter.

While gutters are as a rule arranged horizontally, it may, on occasion, be desired to arrange them at an incline, i. e., "laid to fall." The present invention permits this to be done, without any alteration to the gutter-sections and joints, but with the employment only of a special base plate or fillet having an inclined upper supporting surface. This arrangement is shown in Figs. 7, 8 and 9.

In Fig. 7, the arrows indicate the direction of fall of the gutter. The upper edge of the back A of the gutter is gripped by the clamping strip L which is fixed horizontally. The bottom surface or soffit of the base C of the gutter rests on the inclined upper supporting surface of the special base fillet N, the soffit or under surface of which lies horizontally. In Fig. 8, the relative positions in cross-section of the gutter, clamp L and base fillet N at the lowest point are shown. In Fig. 9, the positions of these parts at the highest point are similarly shown.

As will be appreciated, the clamping strip L and base fillet N overlap the top of the back A and the flange J sufficiently to enable an effective hold to be obtained thereon along the gutter from end to end, notwithstanding the slope of the gutter.

The final appearance of a roof-gutter as above-described is illustrated in Fig. 11, which shows the gutter in relation to the eaves of a building when viewed from below. With a back outlet P, as shown, it is possible for the adjoining discharge pipes, offsets and channels to be concealed within a slatted boarding or boxed-in eaves or solid cornice of a building.

Referring to Figs. 12 to 15:

In the gutter shown in these figures, the end of one gutter-section X (see Fig. 12) is formed with a spigot having sides D, E and a base F. The end of the other gutter-section Y (Fig. 12) is formed with a socket G which is recessed in the floor of the base C of the gutter and which is made of considerably greater length than (e. g., two and a half times) the length of the spigot base F.

Within the limits set by the increase or surplus in the length of the socket G, as compared with the spigot F, the length of any sections such as X and Y of the gutter as a whole can be varied by cutting away or removing more or less of the socketed end of the section. In Fig. 12, no part of the socket G has been cut away. In other words, the socketed end of the gutter-section is in its originally manufactured condition. In practice, according to the exigencies laid down by the length or perimeter of the roof to which the gutter is to be applied, the socketed end of the gutter-sections may be left in this original state, or, as just stated, a part—greater or smaller within the limits indicated—of the socketed end may be cut away.

In Fig. 13, a joint is illustrated in which the end of the socket G has been cut away for the purpose just mentioned to the full extent permitted by the aforesaid limits, so that, as will be seen from the said figure, the socket G is substantially equal in

length to the spigot F, which fits exactly within the socket G.

In cases in which (corresponding to the exigencies stated) no part has to be cut away from the end of the socket G, or in which only a part smaller than the surplus length of the socket has to be cut away, the space S (see Fig. 12) remaining between the end of the spigot F and the step or root R of the socket G will be filled-in so as to be flush with the floor of the base C of the gutter, as will now be more particularly described with reference to Figs. 14 and 15.

In the joint shown in Fig. 14, a small part has (to suit exigencies as aforesaid) been cut away from the end of the socket G and the space S remaining between the end of the spigot F and root R of the socket G is filled-inflush with the floor of the base C of the gutter by means of a pre-cast slab T, which is held in place by cement grouting or otherwise.

In Fig. 15, a somewhat larger part has, it is assumed, had to be removed from the end of the socket G, and the relatively shorter space S between the spigot F and root R of the socket G is filled-in with cement or other suitable plastic or mouldable material V cast in situ.

In all respects other than those above-described, the gutter referred to in connection with Figs. 12 to 15 is similar to that described with reference to Figs. 1 to 11.

The gutter and all the component parts can be manufactured in asbestos, wood, clay, plastic or other suitable material and can be cast, moulded, cut or shaped to the requisite form and can be assembled and fixed in position on a building by an artisan accustomed to the fixing of roofs and rainwater goods, without any special knowledge or training in respect of the said gutter or component parts. The gutter constituting this invention can be used with any type of roof covering.

The gutter and component parts hereinbefore described and illustrated in the accompanying drawings, may be made to any size or form to suit the nature, size and construction of the roof and obtain the final appearance desired.

I claim:

1. A roof gutter comprising, in combination, a plurality of gutter-sections, a spigot provided on one end of each gutter-section, a socket provided on the other end of each gutter-section and adapted to receive the spigot of an adjoining gutter-section so as to provide a joint with externally-concealed laps and with outer faces and soffit for the gutter which are flush throughout, a clamp adapted to engage with the back of the adjoining gutter-sections at the top thereof, a base member, a projecting member provided on the base of each gutter-section at the back thereof and adapted to be engaged by said base member, and means whereby said clamp and base member are fixed to the eaves or other suitable part of the roof.

2. A roof gutter, as claimed in claim 1, in which the clamp comprises a clamping strip which engages with the back of the adjoined gutter-sections along the whole extent of the top thereof and which serves thereby as a flashing strip.

3. A roof gutter comprising, in combination a plurality of gutter-sections, a spigot provided on one end of each gutter-section, a socket provided on the other end of each gutter-section and adapted to receive the spigot of an adjacent gutter-section so as to provide a joint with externally-concealed laps and with outer faces and soffit for the gutter which are flush throughout, strut means, means for positioning said strut means

in said gutter-sections to reinforce same against external compressive stresses, a clamp adapted to engage with the back of the adjoined gutter-sections at the top thereof, a base member, a projecting member provided on the base of each gutter-section at the back thereof and adapted to be engaged by said base member, and means whereby said clamp and base member are fixed to the eaves or other suitable part of the roof.

4. A roof gutter, as claimed in claim 3, in which the strut means comprises a plurality of cross-struts, and in which the positioning means therefore comprises pairs of opposite grooves which are formed in the inner faces of the gutter-sections and are adapted to hold the ends of the cross-struts.

5. A roof gutter comprising, in combination, a plurality of gutter-sections, a spigot provided on one end of each gutter-section, a socket provided on the other end of each gutter-section and adapted to receive the spigot of an adjacent gutter-section so as to provide a joint with externally-concealed laps and with outer faces and soffit for the gutter which are flush throughout, a covering means for said gutter, a clamp adapted to engage with the back of the adjoining gutter-sections at the top thereof, a base member, a projecting member provided on the base of each gutter-section at the back thereof and adapted to be engaged by said base member and means whereby said clamp and base member are fixed to the eaves or other suitable part of the roof.

6. A roof gutter, as claimed in claim 5, in which said covering means comprises a grid, and means for supporting said grid within the upper part of said gutter.

7. A roof gutter comprising, in combination a plurality of gutter-sections, a spigot formed on one end of each gutter-section, a socket formed on the other end of each gutter-section and adapted to receive the spigot of an adjoining gutter-section so as to provide a joint with externally-concealed laps, a clamp adapted to engage with the upper part of adjoined gutter sections, a base plate, a downwardly-projecting flange formed on the base of each gutter-section and adapted to be engaged by said base plate, and means whereby said clamp and base plate are fixed to the eaves or other suitable part of the roof.

8. A roof gutter comprising, in combination, a plurality of gutter-sections, a spigot formed on one end of each gutter-section, a socket formed on the other end of each gutter section and adapted to receive the spigot of an adjoining gutter-section a clamp adapted to extend downwardly over the upper edge of adjoined gutter-sections, a base plate having an inclined upper supporting surface on which the soffit of the gutter is adapted to rest when it is to be laid to fall, a projecting member provided on the base of each gutter-section and adapted to be gripped by the inner edge of said base plate, and means whereby said clamp and base plate are fixed in horizontal disposition to the eaves or other suitable part of the roof.

9. A roof gutter comprising, in combination, a plurality of gutter-sections, a spigot provided on one end of each gutter-section, a socket provided on the other end of each gutter-section and made of greater length than said spigot so that said gutter-section can have a portion removed from the socketed end thereof to conform to the overall length of guttering required, a clamp adapted to engage with the back of the

adjoined gutter-sections at the top thereof, a base member, a projecting member provided on the base of each gutter-section and adapted to be engaged by said base member, and means whereby said clamp and base member are fixed to the eaves or other suitable part of the roof.

10. A roof gutter, as claimed in claim 9, in which, in cases in which removal of the surplus length of the socket is not required, or required only to an extent less than the whole of said surplus length, means is provided for filling-in the space between the end of said spigot and root of said socket and thereby preserving the continuity of the floor of the gutter.

ALFRED HAROLD HONIKMAN.
